N. Y.

Application April 30, 1937, Serial No. 139,881

2 Claims. (Cl. 153—54)

This invention relates in general to roller levelers having comparatively small diameter straightening rolls and supporting or backing rolls placed along the straightening rolls, and more particularly to roller levelers of this type wherein the straightening roll ends and certain of the backing rolls are adjustable relatively to each other. Reference is made to my U. S. Patent No. 2,009,508, issued July 31, 1935. Various applications and constructions embodying this principle of control of the straightening roll contours are disclosed therein.

A definite control of the straightening roll contours which may be also referred to as the working contours or deflection contours of the straightening rolls, is essential for making corrections on sheet, strip or plate material, because when the work material leaves the rolling mills, it shows certain distortions which are usually called the mill shape of the material.

The great majority of the sheets has two distinctly different mill shapes, namely, the middle portion of the sheet may be shorter than the edges, or vice versa. These so-called regular mill shapes may be effectively corrected by apparatus such as disclosed in the aforementioned patent.

However, certain sheets possess other defects in their mill shape. These so-called irregular mill shapes usually consist in longer or shorter areas between the middle portion of the sheet and each edge area.

It will be noted that regular mill shapes may be corrected by flexing the straightening rolls either into convex or concave contours, depending on whether the middle portion of the sheet needs stretching or the edge areas.

For flattening and leveling sheets of irregular mill shape it is necessary to direct the stretching pressure on the short areas, which, as pointed out, are usually located between the middle and the edges of a sheet. These areas will also be referred to as intermediate areas of the sheet and may either consist of two short areas located substantially symmetrical to the middle, or of one short area which may be located in between the middle portion of the sheet and one of its edges.

It is obviously desirable that sheet straightening equipment is adapted to flatten work material of regular and irregular mill shapes efficiently.

The primary object of this invention is to provide means whereby either one or both intermediate areas of a sheet may be effectively stretched.

Another object is to provide means for stretching intermediate areas of sheets or similar work material in combination with mechanisms for deflecting the straightening rolls into convex or

concave contours for stretching sheets of regular mill shapes.

A further object is to provide a roller leveler which may be quickly and positively adjusted for the flattening of sheets of regular and irregular mill shape by providing novel indicating devices in connection with the machine.

These and other objects, to be pointed out in the specification and especially in the claims, I attain by means of my invention disclosed in the accompanying drawings in which:

Fig. 1 is a front view of a roller leveler in section along line 1—1 Fig. 3.

Fig. 2 illustrates a partial sectional top view of the deflecting mechanism along line 2—2 Fig. 1.

Fig. 3 is a side view of the machine shown in Fig. 1.

Fig. 4 depicts an enlarged sectional view of indicating dial along line 4—4 Fig. 3.

Fig. 5 shows in diagrammatic form one of the possible multi-curved working roll contours obtainable by means of the mechanism shown in Figs. 1 to 4.

Fig. 6 is a sectional front view of a modified form of the lower part of the leveler shown in Fig. 1.

Fig. 7 shows a partial sectional top view of the deflecting mechanism along line 7—7 of Fig. 6.

Fig. 8 depicts a partial side view of the machine shown in Fig. 6.

Fig. 9 illustrates diagrammatically a multi-curved deflection of the straightening rolls by means of the construction shown in Figs. 6 to 8.

Referring to Figs. 1 to 5, the leveler embodying the principles of the present invention by way of example may comprise a lower base member 1 carrying lower straightening rolls 3 and associated mechanisms and an upper detachable section 2 with upper straightening rolls 4 and their associated mechanisms. The upper straightening rolls 4 are generally arranged in staggered order with respect to their cooperating lower straightening rolls 3 for the purpose of subjecting the work material to gradually decreasing corrugations between these banks of straightening rolls.

The rigid frame 5 of upper section 2 supports at its outer ends the upper row of straightening rolls 4. Supporting rolls 6, rotably mounted on frame 5 and located in staggered order to upper rolls 4, prevent these straightening rolls from deflecting under load. Another conventional arrangement would be the location of the supporting rolls on top of each straightening roll instead of the staggered relation shown. Both methods of mounting are well known in the art and do not form part of this invention.

Frame 5 may be raised, lowered or tilted with respect to the horizontal plane of the lower

straightening rolls 3 by means of two handwheels 7 on rotatable shafts 8. Two worms 9, 10 engaging respective worm-wheels 11, 12 are mounted on each shaft 8. Worms 10 are fast to shafts 8, while worms 9 are mounted loosely on these shafts. Through the threaded hub of each worm-wheel 11, 12 extends a correspondingly threaded, vertically placed tie-rod 13. Each of these tie-rods 13 is hinged to one of the four corners of the lower base member 1. The upper frame 5 is counterbalanced by means of helical springs 14 on tie-rods 13 to facilitate the adjustment.

Each worm 9 on shafts 8 may comprise one half 15 of a jaw clutch. The other halves 15 of the clutches are slidably keyed to shafts 8. Hence, with clutches 15 in engagement, the upper frame 5, together with straightening rolls 4 and their associated supporting or backing rolls 6, may be 20 raised with respect to lower straightening rolls 3 by rotating handwheels 7. It will be noted that with clutches 15 engaged, both ends of the straightening rolls will be raised or lowered equal amounts.

25 When clutches 15 are disengaged, it is possible to rotate worms 10, while worms 9 remain inoperative. This arrangement gives the possibility to tilt the upper straightening rolls 4 longitudinally with respect to lower straightening rolls 3 as shown for example in Fig. 5. The openings between the upper and lower straightening rolls will differ and are seen to become gradually smaller from the left to the right, Fig. 5.

Conversely, the upper straightening rolls 4 may 35 be tilted longitudinally in the opposite direction by first lowering the rolls 4 at both their ends while clutches 15 are in engagement, and by reversing the direction of rotation of handwheels 7 after disengaging clutches 15. The purpose of 40 these adjustments will appear later.

45 The bearing ends 16 of the lower straightening rolls 3 are freely rotatable in bearing bodies 17 which are sustained by bearing supports or pillow-blocks 18. Curvilinear contact surfaces may be provided on bearing blocks 17 and pillow-blocks 18 to permit bearing bodies 17 to change their location whenever rolls 3 are deflected. If desired, the bearing blocks 17 may be unyieldingly connected with pillow-blocks 18 or both elements 50 17 and 18 may be made in one piece.

55 Pillow-blocks 18 are guided on uprights 19 by gibs 54. Each of the two pillow-blocks 18 is adjustable in height by two vertically placed screw spindles 20, 20'. The pitch of thread of corresponding pairs of screws 20, or 20' is identical for the reason that each pillow-block 18 is intended to be moved uniformly upwards or downwards. A worm-wheel 21, 21', respectively, is secured to the shank of each of the screws 20, 20'. Shafts 22, 60 22', held in suitable bearings 23, are located at right angles to the longitudinal axis of the straightening rolls. Each of these shafts 22, 22' carries two worms 24, 24', respectively, and these worms are in mesh with corresponding worm-wheels 21, 21'.

65 Supporting or backing rolls 25, 26, 27 are located underneath and in staggered relation to lower straightening rolls 3. As a matter of example, Figs. 1 to 5 depict three supporting rolls 70 for each straightening roll. Because the supporting rolls are subdivided into three sections, such an arrangement may also be referred to as three section support or three supporting sections.

75 Supporting rolls 25, 26, 27 are mounted at their ends in bearing elements 28. The two outer bear-

ing bodies 28 rest on solid brackets 29 which may be directly secured to base 30, while the centrally located bearing body is carried by a vertically displaceable pillow-block 31 supported by two adjusting screws 32, 33 rotatably mounted in base 30 5 in any suitable manner. Worm-wheels 34, 35 are secured to the shanks of these screws 32, 33 and engage respective worms 36, 37, keyed or otherwise fastened to shaft 38. This shaft is rotatably held in bearings 38, 48 which may either be 10 secured to the top surface of base 30 or be integral with one of the brackets 29 as shown in Fig. 2.

One purpose of the present invention is to provide mechanisms for deflecting the straightening 15 rolls into convex or concave working contours for stretching the middle area or the edge areas of the sheet, respectively; or to deflect the straightening rolls into a double curve or multi-curve such as shown in Fig. 5, for stretching those areas 20 of a sheet which are located in between the middle and the edge areas. The general method of deflecting the straightening rolls employed in the present invention consists in adjusting the ends 25 of the straightening rolls and one or more supporting sections relatively to each other. Referring to the three section supporting arrangement shown in Figs. 1 to 5, it will be noted that convex or concave deflection contours are obtainable by adjusting the straightening roll ends 30 16 in opposite directions to the centrally located supporting section 26. A double curved deflection contour for stretching intermediate areas may be obtained by adjusting the ends of the straightening rolls 3 and supporting section 26 in 35 identical directions.

To accomplish this, a control shaft 41 is arranged which extends from the left hand side or operating side of the machine to the right hand side. This shaft may be rotated by means of 40 handwheel 42. The rotation of shaft 41 is transmitted to each shaft 22, 22' by respective pairs of meshing miter gears 43, 43', mounted on shaft 41 and shafts 22, 22', respectively.

Inasmuch as the operating direction of supporting section 26 must be reversible, two miter gears 44, 45 are provided on shaft 41 for its adjustment. Both miter gears 44, 45 are in mesh with miter 46 which is suitably fastened to shaft 38. Miter gears 44, 45 are not keyed to shaft 41 50 and turn freely on the same as well as in bearings 47 which are shown as part of the bearing brackets for shaft 38. The inner surfaces of these miter gears 44, 45 are provided with jaws 48. Either miter may be engaged by a clutch element 49 which is slidably keyed to shaft 41. Slidable clutch 49 is operatively associated with a lever 51 which in turn is connected with a rod 51 to a control lever 52 located at the operating side of the straightening machine.

A conventional type snap device or catch 53 is located along rod 51 and serves the purpose to definitely locate the position of the lever 52 for engaging either one of miter gears 44, 45 or for maintaining clutch 49 in neutral position as 65 shown in Fig. 2. When handwheel 42 is turned in clockwise direction, shaft 38 will be rotated in clockwise direction when clutch 49 is in engagement with miter 44; shaft 38 will be rotated in counterclockwise direction when miter 45 is engaged.

Miters 43, 43' for the adjustment of the straightening roll ends 16 will always cause shafts 22, 22' to revolve in the same direction as handwheel 42 is turned. Hence, when 75

handwheel 42 is rotated in clockwise direction, right hand worms 24 will rotate left hand screws 20 also in clockwise direction; shaft 22' with right hand worms 24' mounted thereon will turn their associated worm-wheels 21' and right hand screws 20' in counterclockwise direction. Consequently, both pillow-blocks 18 will be lowered. Provided that clutch 49 engages miter 44, shaft 38 will turn at the same time in clockwise direction and its right hand worms 36, 37 will revolve their respective worm-wheels 34, 35 and right hand screws 32, 33 in clockwise direction. This will result in raising the middle supporting section 26, and a regular convex working contour of the straightening rolls 3 will be obtained; conversely, when handwheel 42 is rotated counterclockwise with clutch 49 engaging miter 44, the straightening roll ends 16 will be raised, supporting section 26 will be lowered and when a work sheet passes through the straightening rolls, the lower rolls 3 will assume a concave deflection contour.

When clutch 49 engages miter 45, supporting section 26 will be displaced in the same direction as the straightening roll ends 16. By turning handwheel 42 clockwise, a lowering of both the straightening roll ends 16 and of the supporting section 26 will be accomplished. When the work sheet passes through the straightening rolls, the resulting working pressure will deflect the middle of the straightening rolls 3 down on the lowered supporting section 26. The stationary, non-adjustable supporting sections 25, 27 will resist any deflection of the straightening rolls 3 so that the latter are forced to assume the multi-curved contour shown in Fig. 5, thereby stretching the intermediate areas of the work sheet in preference to its middle and edge areas.

Fig. 5 illustrates an additional feature. The upper straightening rolls 4 are shown tilted longitudinally by means of the two handwheels 7 and clutch mechanism 15 previously described. The opening between the upper and lower straightening rolls 4 and 3, is shown to decrease gradually from the operating side toward the right hand side of the machine. That intermediate area of the work sheet which passes in the vertical plane of the right hand stationary supporting section 27 will therefore be stretched in preference to any other area of the work sheet. If it is desired to stretch an intermediate area which would pass over the left hand supporting section 25, the sheet may be turned end for end and the adjustment employed as shown in Fig. 5, or the upper straightening rolls 4 may be tilted in the other direction so that the roll openings gradually increase from the operating side toward the right hand side of the machine.

When handwheel 42 is turned counterclockwise with miter 45 engaged, straightening roll ends 16 and supporting section 26 will be raised relative to stationary supporting sections 25, 27. Thus, the middle area and both edge areas of the work sheet may be stretched concurrently. This type of working contour is also desirable for certain irregular mill shapes. It will be noted that supporting section 26 may be disengaged at any time and for any adjusting interval by placing control lever 52 in neutral position. Therefore, even more intricate multi-curved working contours may be conveniently created whenever required.

The roller leveler shown is provided with an indicating mechanism to assist the operator in the precise adjustment of convex, concave or

multi-curved working contours and to indicate the differences in amplitude of such settings.

The indicating device comprises an indicating dial 55 provided with two pointers 56, 57. Fig. 4. The small pointer 56 is connected to one of the ends of shaft 58, rotated by means of a left hand spiral gear 59 which is fastened to the other end of this shaft, Fig. 1. Gear 59 engages a matching gear 60 which is mounted on shaft 38. Any rotation of shaft 38 is thereby positively indicated on dial 55 by means of the small pointer 56, and any displacement of section 26 will thus be recorded.

The large pointer 57 is secured to sleeve 61 which surrounds the small pointer shaft 58. Sleeve 61 is freely rotatable in the stationary dial 55. A sprocket wheel 62 is mounted on sleeve 61 and another suitable sprocket wheel 64 provided on shaft 41 with a chain 63 connecting both sprocket wheels. Hence, the large pointer 57 will record any displacement of the ends 16 of straightening rolls 3.

The gearing for rotating the two pointers is preferably, however not necessarily, selected so that the angular movement of both pointers 25 is of the same amplitude and in the same direction for regular convex or concave straightening roll deflection contours. One pointer may then be on top of the other one and in zero position when the straightening rolls are not deflected 30 as shown in Fig. 3. The pointers will then travel together for any regular convex or concave deflection contours and move in opposite directions when multi-curved deflection contours are 35 adjusted.

The operator therefore will always know precisely the relative positions of the straightening roll ends 16 and of the centrally located adjustable supporting section 26. By providing a suitable scale on the dial, as indicated in Fig. 3, the 40 amplitude will also be clearly shown. Consequently, the leveler may be quickly reset from an irregular deflection contour adjustment to a regular one, or to an absolute straight, horizontal position of the straightening rolls. This 45 position will be called the zero position of the straightening rolls as shown for example in Fig. 1.

The mechanism shown in Figs. 6, 7, and 8 illustrates the application of this deflection principle to roller levelers with a greater number of supporting sections. Therefore, like numerals with a 1 or 10 attached in front of the respective tens or unit numbers have been employed for such parts which are identical or similar to corresponding parts in Figs. 1 to 4. The reading of the drawings is thereby facilitated and the description of the mechanism may be shortened.

The need for multiple supporting sections arises when wider sheets have to be flattened, or when the load carrying capacity of the supporting roll bearings has to be increased. In such cases it becomes necessary to provide a greater number of vertically displaceable supporting sections 126, 126', 180, 181.

The two sections 126, 126' are shown to be located symmetrically to the middle of the straightening rolls 103. Therefore, their vertical displacements may be arranged alike. Each pillow-block 131, 131' is adjustable by two screws 70 132, 132' and 133, 133', respectively. Their respective worm-wheels 134, 134', 188, 188' may be interconnected in pairs as shown. All four worm-wheels may thus be rotated by two worms 136, 137 on shaft 138. A miter gear 146 and 75

148' is secured to each end of this shaft. The end bearings 117 of the straightening rolls 103 are raised or lowered in a similar manner as previously described, by means of screws 120, 120', associated with worm-wheels 121, 121' and worms 124, 124'.

Two control shafts 141, 122 are provided and connected by chain drive 181. Worms 124, 124' for rotating worm-wheels 121, 121' are mounted directly on these shafts. To deflect straightening rolls 103 into regular convex or concave contours, the ends 116 of the straightening rolls and the supporting sections 180, 181 have to be displaced in respective opposite directions to the displacement of the supporting sections 126, 126'. Supporting sections 180, 181 have to be displaced smaller distances than the straightening roll ends 116. Worm-wheels 135, 135' of sections 180, 181 are shown to be in mesh with worm-wheels 121, 121' and consequently the ratio of gearing between worm-wheels 121, 121' and 135, 135' has to be suitably selected; or, a finer pitch may be chosen for screws 182, 183 than for screws 120, 120'. When handwheel 142 on shaft 141 is rotated, the supporting sections 180, 181 will always move in definite relation and in the same direction as pillow-blocks 118 carrying the ends 116 of straightening rolls 103.

Shafts 141 and 122 carry respective miter gears 144, 145 which are provided with jaws 148. Meters 144, 145 are freely rotatable on shafts 141, 122, respectively. To alternately engage either one of miters 144 or 145, clutch elements 149 are slidably keyed to shafts 141 and 122. Hand lever 152 together with snap device 153 and arm 159, Figs. 7, 8, will enable the operator to disengage clutches 149 from both miter gears 144 and 145, or to engage clutch 149 with either one of miter gears 144 or 145.

When a regular convex or concave deflection contour of the straightening rolls 103 is desired, control lever 152 is placed in the right hand notch of snap device 153, Fig. 8, thus operatively connecting miter 144 with shaft 141. When handwheel 142 is then rotated in clockwise direction, right hand worms 124, 124' on shaft 141 will rotate their associated worm-wheels 121 and left hand spindles 120 in clockwise direction. Worm-wheels 121, meshing with worm-wheels 135 of supporting sections 180, 181, will revolve right hand screws 182 in counterclockwise direction. Meters 144, 145 cause shaft 138 to turn in clockwise direction and the right hand worms 136, 137 move their meshing worm-wheels 134, 134' and left hand spindles 132, 132' in counterclockwise directions. Worm-wheels 138, 138' mesh with worm-wheels 134, 134', respectively, and are consequently rotated in clockwise direction together with their right hand screws 133, 133'.

When handwheel 142 is rotated clockwise, shaft 122 will also revolve clockwise. Right hand worms 124, 124' on shaft 122 will therefore move their associated worm-wheels 121' and right hand screws 120' in counterclockwise direction. Meshing worm-wheels 135' and their left hand screws 133 will thus be rotated in clockwise directions.

The result of this adjustment will be that the supporting roll banks 126, 126' will be raised, outside supporting sections 180, 181 as well as the ends 116 of the straightening rolls 103 will be lowered and as a consequence, the straightening rolls 103 will be positively deflected into a regular convex working contour.

When handwheel 142 is turned in clockwise direction and clutch 149 is in engagement with

miter 145, which entails shifting of control lever 152 into the left hand notch of snap device 153, all movements will be the same as described before, with the exception that the direction of displacement of the centrally located supporting sections 126, 126' will be reversed. Thus the multi-curved deflection contour shown in Fig. 9 will be obtained when a work sheet passes through the straightening rolls. In Fig. 9, the upper rolls 104 are shown to be in horizontal position. The work sheet will therefore be stretched along both intermediate areas.

Conversely, by rotating handwheel 142 in counterclockwise direction, the middle area and both edge areas of the work sheet will be stretched at the same time. Analogically to the construction shown and described in connection with Figs. 1 to 5, other multi-curved straightening roll contours may be obtained by engaging supporting sections 126, 126' only part of the adjusting cycle.

The indicating mechanism with its dial 155 and its two pointers 156, 157 is similar to that previously described. The two pointers are again operated from two separate shafts 158, 122. A gear reduction 178 and helical gears 159, 160, Fig. 6, are interposed for actuating the small pointer 156, while the large pointer 157 is driven directly from shaft 122 by chain drive 187, Fig. 8. A more detailed description of this indicating mechanism is believed unnecessary due to its similarity with that described in connection with Figs. 1 to 4.

Various modifications of the mechanism shown will be obvious to those skilled in the art. Thus the principle may be adapted to the conventional method of straightening roll deflection; the stationary supporting sections may be located at different points along the straightening rolls; or different types of indicating devices or different reversing means may be employed without departing from the spirit of the present invention.

I claim:

1. A deflecting mechanism for the straightening rolls of roller levelers comprising in combination with said straightening rolls, adjustable and non-adjustable supporting means for supporting said straightening rolls, adjustable elements for raising or lowering the ends of said straightening rolls, adjustable means for effecting the displacement of said adjustable supporting means with respect to said non-adjustable supporting means; means to connect operatively and selectively said adjustable supporting means and said adjustable elements in such a manner that said adjustable supporting means are displaceable in opposite direction to or in identical direction as said adjustable elements.

2. In mechanisms of the character described, straightening rolls, adjustable and non-adjustable supporting means for said straightening rolls, means for displacing the ends of said straightening rolls and their associated adjustable supporting means relatively to each other for a deflection of said straightening rolls into regular convex or concave working contours, clutch mechanisms for reversing the direction of displacement of certain of said adjustable supporting means for the formation of irregular working contours of said straightening rolls, and one centralized indicating device concurrently denoting the precise respective locations of said displaceable straightening roll ends and of their associated adjustable supporting means.
